United States Patent Office

Des. 180,504
Patented June 25, 1957

180,504

CAPELET OR THE LIKE

Ross Beaumont, Highland Park, Mich.

Application November 10, 1955, Serial No. 38,819

Term of patent 14 years

(Cl. D3—3)

FIG. 1.

FIG. 2.

FIG. 3.

FIG. 4.

FIG. 5.

Figure 1 is a front perspective view of a capelet or the like showing my new design, with the collar in raised position;

Figure 4 is a front perspective view with the collar in its lowered position; and

I claim:

The ornamental design for a capelet or the like, as shown.
